ROBERT L. DORSEY, OF INDIANAPOLIS, INDIANA

IRONING BOARD

Application filed December 20, 1926. Serial No. 155,887.

It is the object of my invention to produce a collapsible table, for ironing or other purposes, which can be compactly folded and which when extended in working position will be very rigid and stable. A further object of my invention is to so construct my table that the natural tendency of the board to warp in service will be counteracted.

10 I accomplish the above objects by constructing my table with two legs which support the top when extended and which fold closely against the top when collapsed, and I provide a brace which acts between the 15 two legs and the table top and when in place strains all parts of the structure slightly so that there will be no lost motion between the parts of the table when it is extended in position for use.

20 The accompanying drawing illustrates my invention: Fig. 1 is a perspective view of an ironing table extended in working position. Fig. 2 is a perspective view showing the legs of the table in partially extended position; Fig. 3 is a fragmental side elevation in partial section illustrating the latch by means of which the brace is held in place; and Fig. 4 is a perspective view of the latch removed from the top.

25 My table comprises a top 10 to the under-surface of which near one end of the board are affixed two U-shaped brackets 11 which serve as a mounting for the legs of the table, such legs being pivotally mounted in 30 the brackets 11 by means of a pin 12 which may extend through both brackets. The front leg 13 of the table consists conveniently of a single strip of wood mounted on the pin 12 between the two brackets 11. 35 The upper end 13' of the leg 13 is made long enough so that it will engage the under surface of the top 10 and limit outward movement of the leg 13 to the oblique position shown in Figs. 1 and 2.

40 The rear leg of the ironing table is a double leg formed of two strips 15 and 16 which are pivotally mounted by means of the pin 12 and which preferably diverge as they extend away from such pin. The two strips 15 and 16 are connected rigidly to-

gether by means of one or more cross braces 17. In the drawing, I have shown two of the cross braces 17 between which there extends two laterally spaced strips 18.

To the strips 18 there is pivotally attached 55 one end of a brace formed of two spaced strips 19 which receive between them the leg 13 and are provided with an abutment in the form of a cross pin 20 adapted to bear against the top surface of the leg 13 60 when the table is extended. Extending between the two members 19 and the brace at their free ends is a second abutment or tongue in the form of a cross piece 22 which is conveniently formed of sheet metal. 65

Located in a predetermined position on the under surface of the table top is a latch 23 which engages the abutment 22 and locks the brace 19 in position when the table is extended. The latch 23 comprises a flat 70 plate 24 adapted to be secured to the under surface of the top 10 as by means of screws 25. Projecting outwardly from the plate 24 is a tooth 26 adapted to engage the strip 22 to hold the brace in place. To prevent 75 the strip from becoming accidentally dislodged from behind the tooth 26, I provide a retainer 28 conveniently formed of spring sheet-metal and secured in place between the plate 24 and the top 10 of the ironing table. 80 The retainer 28 extends downward through a hole 29 in the plate 24 and is provided at the proper place with a shoulder 30 which engages the edge of the strip 22 and holds such strip in contact with the tooth 26. 85

While the brace 19 is in position with the table extended, the upper ends of the two members composing the brace 19 straddle the plate 24 and prevent any lateral movement of the brace or of the front leg 13. 90

When my table is folded, the front and rear legs and the brace 19 lie against the lower side of the top 10 so that the table occupies relatively small space. When it is desired to set the table up, the legs are swung outward about their pivotal mounting on the pin 12, outward movement of the leg 13 being limited by engagement of the end 13' thereof with the lower side of the top 10. 95 Outward movement of the rear legs is limit-

ed by engagement of the pin 20 with the upper surface of the front leg 13. As the free end of the brace 19 is moved toward the top 10, the free end eventually engages the under surface of the top 10 slightly before the strip 22 engages the latch-tooth 26. The further movement of the brace 19 which is necessary to cause the abutment 22 to engage the latch-tooth 26 causes a deflection of the parts of the ironing board, particularly of the front leg 13, as such deflection is necessary to permit the brace 19 to move sufficiently to bring the strip 22 into engagement with the latch-tooth 26. When the strip 22 is engaged behind the latch-tooth 26, the elasticity of the parts which have been strained tends to move the upper end of the brace 19 to the right in Fig. 3; and as this movement is prevented by the engagement of the tooth 26 and the strip 22, the table is locked in open position. To collapse the table, the retainer 28 is moved to the dotted line position shown in Fig. 3 out of engagement with the strip 22, thus permitting removal of such strip from behind the latch-tooth.

When the table is opened, the upward reaction of the end 13' of the front leg 13 and the downward reaction of the strips 15 and 16, tend to bend the board transversely to make its upper surface convex. This counteracts the warping effect which results from alternate dampening and drying of the upper surface of the board.

35 I claim as my invention:

1. A folding table, comprising in combination a rigid top and a collapsible support therefor, said support including a leg pivotally mounted on said top, a brace pivotally mounted on said leg, said brace comprising two laterally spaced bars, a tongue extending between said bars near the free end of the brace, a latch mounted on said top in position to be engaged by said tongue to hold said leg in extended position, and a spring retainer adapted to engage said tongue to prevent accidental disengagement of the tongue and latch.

50 2. A folding table, comprising a rigid top, front and rear legs pivotally attached to said top and adapted to swing to folded position close against the lower surface of said top, means for preventing downward swinging movement of said front leg beyond a predetermined oblique position in which it is disposed between said rear leg and top, a brace pivotally mounted on said rear leg at a point displaced from the axis of pivotal attachment of said rear leg to said top and adapted when the table is extended to extend forwardly and upwardly across said front leg, means on said top for engaging the upper end of said brace to secure it in predetermined position, and an abutment on said brace, the upper surface

of said front leg being uninterrupted and said abutment being adapted to engage such upper surface of the front leg and to slide therealong to force the front leg outwardly as said brace is moved into engagement with said brace-engaging means.

55 3. A folding table as set forth in claim 2 with the addition that said brace is formed of two laterally spaced bars between which said front leg is received, said abutment comprising a cross-pin extending between said two bars.

In witness whereof I have hereunto set my hand at Indianapolis, Indiana, this 9th day of December, A. D. one thousand nine hundred and twenty six.

ROBERT L. DORSEY.
